UNITED STATES PATENT OFFICE.

MALCOLM A. BEESON, OF STILLWATER, OKLAHOMA.

DESIGN FOR A GRAVE MARKER.

Application filed May 17, 1928. Serial No. 26,714. Term of patent 14 years.

To all whom it may concern:

Be it known that I, MALCOLM A. BEESON, a citizen of the United States of America, residing at Stillwater, in the county of Payne and State of Oklahoma, have invented a new, original, and ornamental Design for a Grave Marker, of which the following is a specification, reference being had to the accompanying drawings, forming a part thereof.

I claim:

The ornamental design for a grave marker as shown.

MALCOLM A. BEESON.
